UNITED STATES PATENT OFFICE

100,355

DESIGN FOR A VELOCIPED FRAME

Bert J. Anderson, Hammond, Ind.

Application January 4, 1936, Serial No. 60,422

Term of patent 14 years

To all whom it may concern:

Be it known that I, Bert J. Anderson, a citizen of the United States, residing at Hammond, in the county of Lake and State of Indiana, have invented a new, original, and ornamental Design for a Velocipede Frame, of which the following is a specification, reference being had to the accompanying drawing, forming a part thereof.

Fig. 1 is a side elevational view of a velocipede

frame a part of the steering portion being omitted showing my new design.

Fig. 2 is a top plan view thereof.

Fig. 3 is a front elevational view, and

Fig. 4 is a rear elevational view of the frame.

I claim:

The ornamental design for a velocipede frame, as shown.

BERT J. ANDERSON.
